UNITED STATES PATENT OFFICE.

HELEN TIEDE, OF HOBOKEN, NEW JERSEY.

CLOTHESLINE COVERING.

Application filed August 15, 1924. Serial No. 732,160.

To all whom it may concern:

Be it known that I, HELEN TIEDE, a citizen of the United States, residing at Hoboken, in the county of Hudson and State of New Jersey, have invented certain new and useful Improvements in Clothesline Coverings, of which the following is a specification.

This invention relates generally to clotheslines, the invention having more particular reference to a covering for clotheslines which may be projected over the line when desired.

The invention has for an object the provision of a novel device of this sort which may be readily collapsed or extended over the line.

For further comprehension of the invention, and of the objects and advantages thereof, reference will be had to the following description and accompanying drawing, and to the appended claims in which the various novel features of the invention are more particularly set forth.

Fig. 1 of the drawing is a side view showing a clothesline having the invention applied thereto.

Fig. 2 is a plan view thereof.

Fig. 3 is a detail longitudinal sectional view of the collapsible cover, this view being taken on the line 3—3 of Fig. 4.

Fig. 4 is a transverse sectional view taken on the line 4—4 of Fig. 3.

Referring now to the drawing the reference numeral 16 indicates a clothesline which is looped over a pair of pulleys 11 on the wall 12 of a house adjacent the window of the latter, and a third pulley 13 on a post 13' or the like, this pulley 13 being of considerable diameter. The pulleys 11 are supported by the brackets 14 and the pulley 13 may be supported by a bracket 15. These pulleys are mounted on vertical axes, the two reaches of the line 16 lying in a common horizontal plane. Each of the brackets supports a second pulley, the pulleys on the brackets 14 being numbered 18 and the pulley on the bracket 15 being numbered 19. Looped over these pulleys is a cord or rope 20 to which the covering elements are attached, this cord or rope extending above the line 16.

As here shown there is a covering element for each reach of the line 16 and each of said elements comprises a cloth member 24 attached to a series of transverse plates 25 having legs depending therefrom, the cord

passing freely through apertures in all but the plate 25' at one end, which latter is attached to the said cord as indicated at 26 in Fig. 3. This end plate is movable, while the other end plate, indicated specifically at 25", is fixed. The end plate 25", of the cover element which is near the house, has projecting therefrom a fin or web 28 to which the free ends of a pair of parallel arms 29 are pivotally attached, these arms being pivoted at their opposite ends to a suitable fixed member 29' on the house wall 12, to swing vertically. Projecting from the upper one of these arms 29 and integral therewith is a handle 30 the free end of which is adapted to be engaged by a hook 31 swingably held in the eye of a member 31' secured on the wall 12 to hold the cover element in raised position when the clothes are being placed on the line. The corresponding end plate of the other cover element may be attached to a fin or web 33 projecting from the bracket 16'.

It is believed that the manner of use of my improved clothes line attachment will be readily understood from the above description, it being apparent that the covering element may be projected over the line or drawn back as desired by moving the cord or rope.

Having thus described my invention, what I claim as new and desire to protect by Letters Patent of the United States is as follows:

1. In combination with a clothes line, a rope extending along said line above the latter, and a collapsible cover element for the clothesline connected to the said rope to be moved by the latter between collapsed and extended positions.

2. In combination with a clothes line, a rope extending along said line above the latter, and a collapsible cover element for the clothesline connected to the said rope to be moved by the latter between collapsed and extended positions, said cover element comprising a cloth hood, and a number of transverse plates to which the said hood is attached.

3. In combination with a clothes line, a rope extending along said line above the latter, and a collapsible cover element for the clothesline connected to the said rope to be moved by the latter between collapsed and extended positions, and means for raising and lowering said cover element.

4. In combination with a clothes line, a rope extending along said line above the latter, and a collapsible cover element for the clothesline connected to the said rope to be moved by the latter between collapsed and extended positions, and means for raising and lowering said cover element, com-

prising a pair of parallel arms pivoted at one end to a fixed part and connected at their opposite ends to the said cover element. 10

In testimony whereof I have affixed my signature.

HELEN TIEDE.
